UNITED STATES PATENT OFFICE.

JOHN SPARKS, OF KIMBERLY, CALIFORNIA.

TELEPHONE-TRANSMITTER.

978,070.

Specification of Letters Patent.

Patented Dec. 6, 1910.

Application filed March 30, 1910. Serial No. 552,290.

To all whom it may concern:

Be it known that I, JOHN SPARKS, citizen of the United States, residing at Kimberly, in the county of Shasta and State of California, have invented new and useful Improvements in Telephone-Transmitters, of which the following is a specification.

My invention relates to telephone transmitters, and pertains especially to what I term a "pneumatic microphone transmitter."

The object of the invention is to provide a simple, practical means for intensifying the sound vibrations so as to enable heavier battery currents to be used, and therefore greater electro-motive force and current in the secondary or receiver circuit.

The invention consists of the parts and the construction and combination of parts as hereinafter more fully described and claimed, having reference to the accompanying drawings, in which—

Figure 1 is a section through the invention with the circuits represented diagrammatically. Fig. 2 is a plan view of the stationary carbon disk showing the pockets of granular material.

A is a sound-box or base or a metal case open at the back, and provided with a telephone mouth-piece 2 and metal diaphragm 3. At the back and secured to the case by a yoke or open web 4 is a cylinder 5 or valve chest with its center line of bore directly in line with the center of the diaphragm. The cylinder 5 has an inlet opening 6 at the top midway of its length for the admission of compressed air from any suitable source of supply; and opposite and to either side of port 6 are two pairs of slits 7—8—9—10 at the bottom forming outlet ports, each pair

40 7—8 and 9—10 of slits at either end leading into a respective small chamber with an outlet 11—12, these outlets 11—12 connected by a respective tube 13—14 with the microphone B, as will be shortly described.

45 Within the cylinder 5 and accurately fitted and free to vibrate there is a balanced valve 15 of the spool type made of metal or other suitable substance. This valve is connected to the diaphragm by a small bolt or rod 16 and can be so adjusted that when normal its heads at either end will not quite cover and close any of the ports 7—8—9—10.

The microphone B consists of a metal cyl-

inder 17 of short length and rather large diameter, with an internal annular flange 18 receiving a carbon ring 19 driven in tightly and making electrical connection with the cylinder 17. The ring 19 has six, more or less, circular pockets at either side made by cementing a small ring 20 of floss or yarn to the face. The pockets are filled with granular particles of carbon 21, against which, and on either side of the carbon ring 19, bear the vibrating carbon disks 22 which are attached to the metal diaphragms 23 and insulated electrically from the cylinder 17, except through the stationary carbon ring 19 and the granular particles of carbon 21. The diaphragms 23 and carbon disks 22 are tied together mechanically by a piece of vulcanized fiber 24 or other non-conducting material which passes through the center of the carbon ring 19 and is free to vibrate; a screw 25 passing through a hole in each diaphragm and disk into a female thread in the fiber to complete the tie.

Each diaphragm 23 and its disk 22 are free to vibrate in a respective chamber 26 formed between a diaphragm and a head 27 of cylinder 17, and each chamber 26 is connected through a port 28 with a respective tube or air duct 13—14. Holes 29 are bored through the walls of the cylinder 17 into the disk chambers 26 inside the diaphragm 23 to communicate with the atmosphere. The diaphragms rest on a rubber ring 30 on a shoulder formed by the larger bore of the cylinder 17 which receives the heads. The ports 28 are at the center of each of the heads and are rounded off at their edges to insure easy admission of air from the valve chest 5.

Each diaphragm 23 is connected by a wire 31 passing through an insulated hole in the walls of the cylinder 17; and each wire connects through a separate battery 32 with the primary winding 33 of a separate induction coil, thence returning to the body of the cylinder by wire 34 to make connection with the carbon ring 19. The batteries 32 are so connected that the current passes through the primary windings of the coils in opposite directions. The secondary windings 35 of the coils are connected in series, thence out over the line 36 and through the receiver 37 at the other end.

In operation, a pressure of air through port 6 at anywhere above atmospheric pressure entering the valve chest 5, with the valve 15 in normal or vertical position, will flow 5 down against each head of the balanced valve through the ports 8-9 which are partly uncovered by the heads of the valve, and out through the exhaust ports 7-10 which are also left partly uncovered. At the same time 10 there will be pressure applied on each of the diaphragms 23 in the microphone, but being equalized, they will balance, and no disturbance of the electrical resistance of the transmitter will result, and therefore, no sound 15 in the receiver; but any movement of the diaphragm 3 of the mouth-piece will cause a movement of the valve 15 in the air chest 5, which will uncover, more or less, one or the other of the supply ports 8-9 and cover, 20 more or less, one or the other of the corresponding exhaust ports 7-10. Of course, the vibrations of the diaphragm 3 due to the talking into the mouth-piece 2 will result in the very rapid reciprocation or flutter of the valve 15, and of course the reaction on the diaphragms 26 will be very rapid. That is to say, a movement of diaphragm 3 toward valve chest 5 will cause 25 valve 15 to close, more or less, both the ports 9 and 7. This will cause a rise in pressure in diaphragm chamber 26 to the left through tube 13 and port 28 and result in compressing the granular carbon particles 21 on that 30 side of the fixed carbon disk 19. At the same time pressure is reduced in the opposite chamber 26 and relieving the pressure 35 on the carbon particles on that side. Simultaneously with these movements an increase of current due to the compression of the loose carbon on the left will flow from the right-hand battery 32 through its primary coil 33, while the flow of current through the other primary will be decreased. The result 40 will be a strong impulse of current through the secondaries of the coils in the same direction, and a movement of the diaphragm in the receiver at the end of the line. When the diaphragm 3 vibrates to the right, or 45 away from the valve chest 5, the action is reversed. It is naturally understood that these vibrations occur very rapidly and the valve 15 is kept in a constant flutter all the time while one is talking, alternately admitting a greater pressure to one chamber 26 and 50 reducing the pressure in the opposite chamber 26. Hence, any vibration of the diaphragm at the mouth-piece end will cause similar vibration of the spool valve and through the compressed air vibrate the 55 larger diaphragm of the microphones and varying the electrical resistance and cause waves of current to flow and vibrate in the receiver, reproducing sound waves made at the mouth-piece.

When using the device the air pressure is 65 constant through the inlet 6, and this air pressure may be anywhere from one ounce to one hundred pounds, more or less.

The object of applying compressed air to the transmitter is to obtain an increase in 70 strength of the vibration of the microphone, enabling heavier battery currents to be used and therefore greater electro-motive force and current in the secondary or receiver circuit. 75

Having thus described my invention, what I claim and desire to secure by Letters Patent is—

1. The combination with a mouth-piece having a diaphragm, of a valve-chest to receive fluid under pressure, a balanced-valve operable in the valve chest and connected to and movable with the mouth-piece diaphragm, and mechanism controlled by the valve and exposable to the fluid pressure 85 for electrically reproducing sonorous vibrations of the diaphragm.

2. The combination of a mouth-piece, a mouth-piece diaphragm, a valve chest, a balanced valve therein connected with said diaphragm, said valve chest connected with a source of fluid pressure supply, mechanism including suitable circuits and receiving mechanism for electrically reproducing sonorous vibrations, and means by which 95 said mechanism is operated by the vibration of said valve.

3. The combination of a suitably supported fixed carbon disk, vibrating carbons on each side thereof, diaphragms carrying 100 said vibrating carbons, connections between the vibrating carbons whereby they vibrate in unison, a granular carbon body between each vibrating carbon and the fixed carbon, a telephone mouth-piece and diaphragm, 105 pneumatic means controlled by the mouth-piece diaphragm for actuating the first-mentioned diaphragms, and electrical mechanism controlled by the vibrations of said first-mentioned diaphragms. 110

4. The combination of a suitably supported fixed carbon disk, vibrating carbons on each side thereof, diaphragms carrying said vibrating carbons, connections between the vibrating carbons whereby they vibrate in 115 unison, a granular carbon body between each vibrating carbon and the fixed carbon, said diaphragms vibrating in fluid chambers, means for alternately increasing the pressure in one chamber and decreasing the 120 pressure in the other, and means for alternately reproducing the vibrations of said diaphragms.

5. The combination of a suitably supported fixed carbon disk, vibrating carbons on 125 each side thereof, diaphragms carrying said vibrating carbons, connections between the vibrating carbons whereby they vibrate in

unison, a granular carbon body between each vibrating carbon and the fixed carbon, fluid chambers in which said diaphragms vibrate, a valve chest having ports connected with said chambers, a telephone mouth-piece, a diaphragm actuated by the vibrations in the mouth-piece, a valve in the valve chest, connections between the diaphragm and valve, a receiver, and electrical connec-

tions between the receiver and said diaphragms in said fluid chambers.

In testimony whereof I have hereunto set my hand in the presence of two subscribing witnesses.

JOHN SPARKS.
